UNITED STATES PATENT OFFICE.

MORTON G. BUNNELL, OF PORTER, INDIANA, ASSIGNOR TO AUSTIN MANUFACTURING COMPANY, OF CHICAGO, ILLINOIS, A CORPORATION OF ILLINOIS.

CRUSHER.

No. 926,725.

Specification of Letters Patent.

Patented July 6, 1909.

Application filed April 20, 1908. Serial No. 428,034.

To all whom it may concern:

Be it known that I, MORTON G. BUNNELL, a citizen of the United States of America, and resident of Porter, Porter county, Indiana, have invented a certain new and useful Improvement in Crushers, of which the following is a specification.

My invention relates to jaw-crushers of the type shown, for example, in Letters Patent Number 839,103, issued December 25, 1906, for improvement in crushing machines. In these jaw-crushers, as is well known, it is desirable that the dies or crushing faces of the two opposing jaws be adjustable toward and away from each other, by the insertion of gibs or shims behind the same, whereby the shape and size of the crushing hopper may be changed or varied with respect to different kinds of material, or for the purpose of varying the size and character of the product. My invention is, therefore, addressed primarily to the problem of readily inserting and removing the said gibs or shims with as little inconvenience or labor as possible, so as to change the relative positions of the said dies or crushing faces of the jaws, and of securely holding the same in place thereon; and with a view to improving the machine and increasing its efficiency in this respect, my invention contemplates a construction by which the gibs or shims can be easily inserted back of the dies or crushing faces of the jaws, without removing the latter, and in which clips or clamping yokes, or other equivalent means, are arranged to embrace the sides of said dies or crushing faces, said clips or yokes, or other clamping means, bearing upon the tops of said dies or crushing faces to hold the same down in place upon the seats provided for their lower ends, and the construction being such that the said dies or crushing faces are also held tightly clamped upon the gibs or shims or other supports provided for their backs; the insertion or removal of said gibs or shims being possible by simply loosening the clamping nuts at the lower ends of said clips or yokes, as will hereinafter more fully appear.

By my invention I am enabled to easily and quickly change the size or shape of the crushing hopper without removing the jaws or any portions thereof.

In the accompanying drawings,—Figure 1 is a sectional side elevation of the crushing hopper of a jaw crusher embodying the prin-

ciples of my invention. Fig. 2 is a detail cross section on line 2—2 in Fig. 1. Fig. 3 is a cross section on line 3—3 in Fig. 1.

As thus illustrated, the crusher frame A can be of any suitable, known or approved construction, and has a seat *a* and a shoulder or overhang *a'*, together with vertical openings or recesses *a*² that extend through said shoulder, permitting the upper end of the yoke B to be moved back and forth horizontally. The clip or yoke B extends vertically in said holes or recesses, and has its lower ends provided with fastening nuts *b* that bear upon the under surface of the shoulder *a'*, as shown. A die or crushing face C rests upon the seat *a*, and the top or upper end of said clip or yoke bears upon the upper end of said die or crushing face. With this arrangement a gib or shim *c* may be inserted back of the die or crushing face, the said clip or yoke being of a size to completely straddle and embrace the upper end of the said die or crushing face, as well as said gib or shim. By loosening the nuts *b*, the said gib or shim can be readily inserted or removed, there being nothing to obstruct the direct downward insertion and upward removal of the same. The forward and back adjustment of the upper end of the yoke B depends, of course, upon the thickness of the shim or shims back of the die.

The movable jaw D can be of any suitable construction, and may be operated in any suitable manner. It has a seat *d* and a shoulder or overhang *d'*, which latter has openings or recesses *d*², as shown, which openings permit forward and back adjustment of the upper end of the yoke B, depending on the thickness of the shim or shims back of the die F. The clip or yoke E straddles the die F and extends through the openings *d*², and has its lower ends provided with clamping nuts *e*, which latter bear upon the under surface of the shoulder *d'*, to hold said die or crushing face in place on the seat *d*, and in position for coöoperating with the other jaw. The said clip or yoke E is much larger than the clip B, and bears upon the top of the die or face plate F, exactly as the clip or yoke B bears upon the face plate or die C, whereby both are securely but removably clamped in place. A gib or shim *f* may be inserted back of the die F, this feature being the same as in the other jaw.

The recesses *a*² and *d*² permit variation in

the inclination of the clips or yokes B and F, as explained, according to the number and shape of the gib or shims back of the dies or face plates.

5. I do not, of course, limit myself to the exact construction shown and described.

What I claim as my invention is:

1. A crusher having crushing instrumentalities including a die or crushing face, 10 means for supporting* the same, clamping means embracing the sides of said die and bearing upon the top thereof to hold the same in place upon said supporting means, and means permitting the upper end of said 15 clamping means to be adjusted back and forth horizontally.

2. A crusher having crushing instrumentalities including a die or crushing face, means for supporting the same, and means 20 including an inverted U-shaped clamping member embracing and bearing down upon said die to hold the same in place upon said supporting means.

3. A crusher having crushing instrumentalities including a die or crushing face, 25 means for supporting the same, an imperforate shim or gib, and retaining means for the die bearing down upon the upper end thereof, permitting direct downward edgewise insertion of said shim or gib at the back thereof.

4. A crusher having crushing instrumentalities including a die or crushing face, an inverted U-shaped member embracing the upper end of said die, bearing upon the upper 35 end thereof, disposed at an angle oblique

thereto, means back of said die for securing the lower ends of said member, and means engaging the lower end of said die to support the same.

5. A crusher having crushing instrumentalities including a die or crushing face, a 40 shim or gib back of said die, a clip or yoke embracing said die and shim and engaging the die, means back of said shim for securing the lower ends of said clip or yoke, and means 45 engaging the lower end of said die to support the same.

6. A crusher having crushing instrumentalities including a movable jaw, a die on said jaw, a clip or yoke embracing the said jaw 50 and die, bearing upon the upper end of the latter, and removable means for fixing the lower ends of said clip or yoke to said movable jaw.

7. The improved crusher jaw, having a die 55 or crushing face therefor, the same provided with an inverted U-shaped clamping member for the said die or crushing face, arranged oblique thereto, whereby the lower ends of said member are some distance from the 60 back of said die and whereby the upper end of said member imposes a downward and backward pull on said die, substantially as shown and described.

Signed by me at Chicago, Illinois, this 8th 65 day of April, 1908.

MORTON G. BUNNELL.
